[57] CLAIM

The ornamental design for a mobile telephone holder, as shown and described.

DESCRIPTION

FIG. 1 is a perspective view of a mobile telephone holder showing my new design;

FIG. 2 is a front end view of the mobile telephone holder shown in FIG. 1;

FIG. 3 is a rear end view of the mobile telephone holder shown in FIG. 1;

FIG. 4 is a side view of the mobile telephone holder as seen from the left side of FIG. 3;

FIG. 5 is a side view of the mobile telephone holder as seen from the right side of FIG. 3;

FIG. 6 is a top view of the mobile telephone holder shown in FIG. 1; and,

FIG. 7 is a bottom view of the mobile telephone holder shown in FIG. 1.

The broken line showings throughout the views are for illustrative purposes only and form no part of the claimed design.
